[57] CLAIM

The ornamental design for a vehicular window, as shown and described.

DESCRIPTION

FIG. 1 is a side elevational view of a vehicular window showing my new design, the opposite side being a mirror image thereof;

FIG. 2 is a top plan view thereof;

FIG. 3 is a bottom plan view thereof;

FIG. 4 is a rear elevational view thereof;

FIG. 5 is a front perspective view thereof; and,

FIG. 6 is a rear perspective view thereof.

The broken line showing of the truck in FIGS. 5 and 6 is for illustrative purposes only and forms no part of the claimed design.
